ELECTRICAL ACTUATION MEANS FOR
VALVES OR THE LIKE

Russell C. Churchman, deceased, late of Des Moines, Iowa, by Nellie Churchman, executrix, Polk County, Iowa

Original application October 29, 1945, Serial No. 625,225. Divided and this application February 15, 1951, Serial No. 211,156

8 Claims. (Cl. 317—141)

1

This is a divisional application from the prior application of Russell C. Churchman for a Mechanism For Draining Accumulated Moisture From Storage Tanks, filed on October 29, 1945 and having Serial Number 625,225, now Patent No 2,552,518.

This invention relates to an electrical actuation means and embodies a novel construction of a solenoid to provide a time control switch within an electric circuit.

More specifically it is the aim of this invention to provide an electric actuation means for actuating a given member, with the electric actuation means connected to a main circuit by which other independent members are actuated and by providing a time control switch on the electric actuation means so that the member to be actuated ceases to be actuated after a predetermined period without interfering with the operation of the other independent members in the circuit.

A further object of this invention is to provide in the electric actuation means above set forth, a means to break the connection from the main circuit to the electric actuation means after the time control switch has broken the connection to the actuated member and thereby provides a means whereby the member to be actuated by this electrical actuation means is actuated only once each time current flows through the main circuit.

Still further objects of this invention are to provide an electrical actuation means having the characteristics above set forth that is automatic in operation, economical to manufacture, durable and efficient in use, easy to install, maintain and adjust.

These and other objects will be apparent to those skilled in the art.

The invention consists in the construction, arrangement, and combination of the various parts of the device, whereby the objects contemplated are attained as hereinafter more fully set forth, pointed out in the claims, and illustrated in the accompanying drawings, in which:

Fig. 1 is an enlarged elevational view of this electrical actuation means and showing an arrangement of a compression system partly in section and partly diagrammatically to illustrate one use for this device, and

Fig. 2 is an elevational view of the hinged arms of the electrical actuation means showing the arms in their fully separated position.

While this device can be adapted for many uses, its operation will be more readily understood by illustrating one specific use. For this purpose it is shown in connection with draining moisture from a storage tank in a compressed air system and a diagrammatic representation of the compressed air system is shown in Fig. 1. When air is compressed, water vapor condenses and accumulates in liquid form in the bottom of

2

the storage tank. For many reasons which are not here material, it is desirable to eliminate this water from the tank and to accomplish this end, this electrical actuation means can perform an important function which will be apparent from the disclosure to be made.

Referring now to the drawings, the numeral 10 designates generally the electrical actuation means which may be mounted on a supporting member 11 which in turn is supported on any member where an actuation action is desired, and in the present instance is shown mounted on the valve 12 as by screw threads 13 which will be referred to later. The electrical actuation means 10 connects electrically with an automatic switch 14 and electric current flows to the electrical actuation means 10 at the same time it flows to any other independent member to be operated thereby, which is illustrated here as being a compressor and motor 15. Mounted on supporting member 11 is an electrically influenced member which in the present instance is a magnetic coil 16 connected electrically with the automatic switch 14. Electric current flowing into magnetic coil 16 magnetizes projecting core 17 which is rounded on top as more clearly shown in Fig. 2. Mounted on the other side of supporting member 11, opposite magnetic coil 16 is another electrically influenced member 18, which in the present instance is a solenoid. The solenoid has a core member 19 therein, which core member 19 is moved downwardly by the solenoid 18 when energized to actuate any given member, illustrated here as the valve 12 that will be later described. Connected rigidly to the top of core member 19 and supported thereby is an arm member 21 having a second arm member 22 hingedly connected to arm 21 at 23. Arm 21 has an electrical contact member 24 connected to the end thereof while arm 22 has a contact member 25 rigidly connected thereto and a spring 26 between arms 21 and 22 keeps contact members 24 and 25 in engagement. The contact member 25 is connected electrically with the automatic switch 14 and is supplied electric current at the same time electric current is supplied a member illustrated by the compressor 15. A time limit switch member 27 connects to the solenoid 18 and conductor 28 to the contact point 24 so that when the points 24 and 25 are in engagement, electric current will flow from switch 14 through point 25 to point 24 and through the conductor 28 and the time switch 27 to the solenoid 18. The switch member 27 has a thermostatic member that is heated by electric current passing therethrough and expands to actuate the switch means 27 to close off flow of electric current to the solenoid member 18. The thermostatic member can be made to allow any time interval desired in which the core 19 will move to actuate any given member.

A compressor 15 furnishes compressed air

through conduit 29 to a storage tank 30 where it is distributed for use through pipe 31. A conduit 32 connects pressure storage tank 30 with automatic switch 14 and automatic switch 14 is so constructed as to be influenced by the air pressure in pressure storage tank 30. It is the usual practice to maintain air pressure in storage tank 30 at a given maximum pressure. When the pressure of air in storage tank 30 reaches this maximum, it is exerted through conduit 32 against automatic switch 14 to close off the automatic switch 14 from supplying electric current to compressor 15 thus stopping the compressing operation. As air is withdrawn from storage tank 30 for use, the pressure in storage tank 30 is reduced and is likewise reduced in conduit 32. When pressure in storage tank 30 and conduit 32 reaches a predetermined low, automatic switch 14 will make contact, allowing electric current to flow to compressor 15 and thus set the compressing operation in operation until pressure in storage tank 30 again reaches the maximum. This operation is standard.

Moisture will accumulate in the tank 30 from the compression of air and it is desirable to remove it. In this connection the electrical actuation means described above is usable to automatically actuate the valve 12 for accomplishing that purpose.

The valve shown generally at 12 comprises a body 33 and an inlet 34 into which conduit 35 connects at one end and at its other end joins storage tank 30. An outlet 36 is provided to receive the conduit 37 which conduit leads to a point of disposal for any accumulated water drained from storage tank 30. A passage 38 runs through the valve body 33 from inlet 34 to outlet 36 to establish a conduit through the valve body 33. Within the valve body 33 is a tapered seat 39 to receive tapered plunger 40 in sealing arrangement to close off passage 38 through the valve body 33. Spring 41 urges the plunger 40 into sealing engagement with seat 39. The plunger 40 has an extension rod 42 extending upwardly through the valve body 33 and outside thereof to contact an actuation means for unseating the valve plunger 40 from the seat portion 39. Spring 41 always tends to urge the plunger into closed position or into engagement with seat 40 to close off passage 38. A screw member 43 may fit across passage 38 in the outlet side of the valve body 33 and may be screwed in or out of the valve body 33 to restrict or enlarge the size of passage. In the compressed air system described, this electrical actuation means is mounted on the valve body 33 so that the core 19 can engage the top of extension rod 42 at times.

In operation, when electric current is supplied to compressor 15, electric current also flows to magnetic coil 16, thus magnetizing projecting core 17 and electric current also flows to electric contact member 25. With the parts in the position shown in Figure 1, contact member 24 is in engagement with contact member 25 hence electric current is conducted from contact member 25 to contact member 24, through conductor 28 to a time limit controlled switch member 27. The switch member 27 has a thermostatic member that is heated by electric current passing therethrough and expands to actuate the switch means 27 to close off flow of electric current to the solenoid member 18. The thermostatic member can be made to allow any time interval desired to hold valve 12 open to drain accumulated moisture from the tank 30. Conductor 28 after con-

necting to the time limit control switch 27 connects into solenoid 18 to furnish electric current to the solenoid 18 when time limit control switch 27 is in contact.

When electric current does not flow to the solenoid 18, it is no longer energized hence core member 19 moves upward to the position shown in Figure 2. When the solenoid is energized, core member 19 is pulled downward, contacting extension rod 42 to unseat plunger 40 from seat 39 to thus open passage 38 through the valve and allow accumulated water in storage tank 30 to drain to a disposal point through conduit 37. The plunger 40 is held unseated for a predetermined interval while air under pressure in storage tank 30 forces accumulated moisture through conduit 35, the valve and conduit 37. The screw 43 may be regulated in passage 38 to enlarge or restrict passage 38 to be sure all moisture is removed from storage tank 30 during the interval the valve is open. When solenoid 18 is no longer energized, core member 19 is moved upwardly and spring 41 forces plunger 40 into closed position across passage 38.

When time controlled switch 27 closes off electric current to solenoid 18, after the predetermined time interval has elapsed, electric current is still being supplied to the magnetic coil 16. The core member 19 moves upwardly about one-quarter inch and the arm member 21 being rigidly attached thereto moves upwardly also. Since the projecting core 17 is still magnetized, it holds arm 22 and will not let arm 22 move upwardly, hence in order for arm 21 to move upwardly arm 22 must hinge about point 23. As seen in Figure 2, the upward movement of arm member 21 separates contact members 24 and 25 hence no electric current can pass to the solenoid until the contact members 24 and 25 are back in engagement again.

The arm members 21 and 22 remain in the position shown in Figure 2 for the time electric current is supplied to compressor 15 or until automatic switch 14 closes off. When this occurs no more electric current is furnished magnetic coil 16 and in turn projecting core 17 is no longer magnetized. Spring 26 then pulls arm 22 upwardly until contact members 24 and 25 are in engagement and the mechanism 10 is all set to operate again when automatic switch 14 is again actuated by a pressure drop in storage tank 30. Electric current again passes to magnetic coil 16 and magnetizes projecting core 17; solenoid 18 is energized thus pulling core member 19 downwardly and also bringing arm 22 into engagement with the projecting core 17. This completes the cycle of operation as the device is back to the position shown in Figure 1.

Some changes may be made in the construction and arrangement of the electrical actuation means for a valve or the like and method of making same without departing from the real spirit and purpose of the invention, and it is intended to cover by the claims, any modified forms of structure or use of mechanical equivalents which may be reasonably included within their scope.

What is claimed is:

1. In combination with a main electric circuit used to operate a separate device, said circuit provided with a switch means, an electrical actuation means, comprising, a magnetic coil connected electrically to said main circuit and magnetized when the main switch is closed, a solenoid with a movable core, a first arm rigidly secured to said core, a contact point on said first arm, a sec-

ond arm hingedly secured to said first arm, a contact point on said second arm capable of engagement with the contact point on said first arm, yielding means normally urging said contact points into engagement, said solenoid electrically connectible to said main circuit through said contact points, a time control means disposed in the electrical connection intermediate said solenoid and said contact points for breaking the electrical circuit to said solenoid, said core when the circuit is broken to said solenoid moving said first arm upwardly and at the same time said coil holding said second arm against said yielding means so that engagement between said contact point is broken, and said coil losing its magnetism when said switch is open whereby said yielding means returns said contact points to engagement with each other.

2. In combination with a main electric circuit used to operate a separate device, said circuit provided with a switch means, an electrical actuation means, comprising, an electrically influenced member connected electrically to said main circuit and energized when the main switch is closed, a solenoid with a movable core, a first arm rigidly secured to said core, a contact point on said first arm, a second arm hingedly secured to said first arm, a contact point on said second arm capable of engagement with the contact point on said first arm, yielding means normally urging said contact points into engagement, said solenoid electrically connectible to said main circuit through said contact points, a time control means disposed in the electrical connection intermediate said solenoid and said contact points for breaking the electrical circuit to said solenoid, said core when the circuit is broken to said solenoid moving said first arm upwardly and at the same time said electrically influenced member holding said second arm against said yielding means so that engagement between said contact points is broken, and said electrically influenced member becoming de-energized when said switch is open whereby said yielding means returns said contact points to engagement with each other.

3. In combination with a main electric circuit used to operate a separate device, said circuit provided with a switch means, an electrical actuation means, comprising, an electrically influenced member connected electrically to said main circuit and energized when the main switch is closed, a solenoid with a movable core, a first arm rigidly secured to said core, a contact point on said first arm, a second arm hingedly secured to said first arm, a contact point on said second arm capable of engagement with the contact point on said first arm, yielding means normally urging said contact points into engagement, said solenoid electrically connectible to said main circuit through said contact points, a time control means disposed in the electrical connection intermediate said solenoid and said contact points for breaking the electrical circuit to said solenoid, said core when the circuit is broken to said solenoid moving said first arm upwardly and at the same time said electrically influenced member holding said second arm against said yielding means so that engagement between said contact points is broken without interfering with the electrical connection between said switch and said separate device.

4. A device as defined in claim 3 wherein the opening of the main switch de-energizes said electrically influenced member whereby said yielding means returns said contact points to

engagement with each other and said solenoid can again be actuated when said switch closes.

5. An electrical actuation means comprising a solenoid with a movable core therein, said core being pulled to one position when electric current is supplied to the solenoid with the core returning to its original position when electric current is not supplied to the solenoid, a thermostatically controlled switch member to close off electric current to the solenoid after a predetermined time interval has elapsed and means for breaking the electrical circuit to the solenoid after the thermostatically controlled switch has closed off electric current to the solenoid including hinged arm members connected to said movable core, said arm members having oppositely disposed engageable contact points through which electric current flows to the solenoid when the contact members are in engagement and the movement of said core when said solenoid is de-energized moving one of said arms to break the electric circuit in the solenoid.

6. In combination, an electrically operable member, a source of electric power for operating said electrically operable member, a switch for said electric power, a second member, means connected to said switch and connecting said second member to said source of electric power, time control means associated with said second member and said first means to close off electric power from said first means to said second member, said second member when electric power is closed off thereto acting on said first means to break its connection with said switch without interfering with the operation of said electrically operable member.

7. A device as defined in claim 6 wherein said second member is actuated only once for a timed interval during each period of operation of said electrically operable member.

8. In a device of the class described, an electrically operable member, a source of electric power for operating said electrically operable member, a switch for said electric power, a solenoid, means connected to said switch and connecting said solenoid to said source of electric power, a movable core in said solenoid, said core connected to said means connecting said solenoid to said electric power, said core being pulled to one position when electric power is supplied to the solenoid whereby it is capable of actuating any member to be actuated, said core returning to its original position when electric current is not supplied to the solenoid, a time controlled switch to close off electric power from said means to said solenoid after a predetermined time interval has elapsed, and the movement of said core when electric power is cut off to said solenoid acting on said means to break the connection between said means and said switch without interfering with the operation of said electrically operable member.

NELLIE CHURCHMAN,
Executrix of the estate of Russell C. Churchman,
deceased.
